UNITED STATES PATENT OFFICE.

FREDERICK W. CHRISWELL, OF SEATTLE, WASHINGTON, ASSIGNOR TO PACIFIC CAR AND FOUNDRY COMPANY, OF SEATTLE, WASHINGTON, A CORPORATION OF WASHINGTON.

CAR BOLSTER.

Application filed July 17, 1922. Serial No. 575,528.

To all whom it may concern:

Be it known that I, FREDERICK W. CHRISWELL, a citizen of the United States of America, and resident of the city of Seattle, in the county of King and State of Washington, have invented certain new and useful Improvements in Car Bolsters, of which the following is a specification.

My present invention is an improvement 10 in car bolsters of a type which are designed for use in conjunction with bunks of a special type, to form an efficient and unusually strong and rugged log carrying means for cars.

15 The object of my invention is to form a strong and rugged log supporting and carrying means for cars. The novel features upon which patent protection is desired will be hereinafter described and particularly pointed 20 ed out in the claims.

Figure 1 is a top plan view of a bunk and bolster of my improved construction, one end of the bunk being broken away.

Figure 2 is an end view of a truck and 25 side elevation of a bolster and bunk, one side of the figure showing these parts in section.

Figure 3 is a transverse section on line 3—3 of Figure 2.

30 As the novel features which comprise my invention are confined to the bolster and to the combination of the bolster with the bunk and of these parts with the longitudinal beams of a car body, I will not particularly describe the truck construction. The latter may be anything which accommodates 35 itself to a suitable combination with the special type of bolster herein described and claimed. The truck has its part 1 of a center bearing, this cooperating with a complementary part 10 of the central member 2 of the bolster. A king pin 11 is also employed. These parts may be of any acceptable construction.

45 The truck also has its part 12 of side bearings. The central beam 2 of the bolster is of a length to carry the complementary upper part 13 of the side bearing.

Bracket extensions 3 are secured to the 50 outer ends of the bolster 2. The manner of securing is such as to make a firm and rigid combination. Liberal flat under surfaces 30 at the inner end of the bracket extensions are securely bolted or riveted to the outer part 55 of the upper surface of the bolster 2. A

transverse rib 31 abutting against the ends of the bolster 2 serve to position the two parts and to assist in taking the inward end thrust of the bracket extensions.

The inner end faces of the bracket extensions stop at such a distance from the center as to form between them a space in which to accommodate the central sills 4 which serve as the backbone connecting the two trucks. The depth of the bracket extensions 3 also 60 65 conforms to the depth of the sills which are to be employed for this purpose.

At its outer end each bracket extension is provided with a recess having two faces at right angles forming a ledge or projecting 70 arm 32 upon which is placed the outer or side sills 40. This recess is of a size to just accommodate the transverse section of such sills. The bracket extensions are also shown as provided with recesses 33 in their upper 75 edge, of which two are shown for each bracket section, one located just inside of the sill-receiving recess at the outer end of the extension and the other just outwardly of its inner end. These are designed for receiving truss rods.

Both the bolster 2 and the bracket extensions 3 are provided upon the sill sustaining upper surfaces with ribs as 34 which extend lengthwise of the extension and transversely 80 85 of the sills 4 and 40 which are carried thereon. The purpose of these is to form a locking tie against longitudinal movement of the sills 4 and 40 which sills are for this purpose grooved so as to form a channel which 90 closely fits the ribs 34.

In conjunction with the bolster as above described, is employed a bunk 5. This bunk is of metal construction. It may be of any suitable type of bunk structure of which a 95 number are on the market. This rests upon the upper surface of the two extension brackets 3 to which it is secured by rivets or bolts so that the bunk forms a tension member and the bolster sections together 100 form a strong and rigid compression member of a truss capable of resisting extremely hard blows and heavy weights. As the particular structure of the bunk is immaterial to my invention I have not illustrated this 105 in detail nor here described the same any more than that it has a metal frame extending integrally throughout its entire length. The above construction of bolster and bunk has been found excellently adapted to the 110

rough use to which it is subjected when used for carrying logs. By extending the bolster section 2 so as to form the upper half of the side bearings thereon, it has been possible to make the whole device more rigid.

The bunk forms an upper or tension member of a truss of which the bolster 2 and the bracket extensions 3 are the compression members. These parts are strongly bolted or riveted together to form an unusually strong and rugged truss capable of sustaining the blows and strains incidental to loading and hauling heavy logs. They are also proportioned to form recesses which snugly receive and securely hold the car sills.

What I claim as my invention is:

1. An extension bracket for car bolsters having a level top for the body thereof adapted to serve as a support for a bunk, an inner end portion thereof having a vertical thickness corresponding to the vertical depth of a car sill and adapted to rest upon and be secured to the outer end of the car bolster, the bracket body extending outwardly of the bolster end and a side-sill supporting arm extending from the outer end of the bracket body at the lower side thereof.
2. An extension bracket for car bolsters having a level top for the body thereof adapted to serve as a support for a bunk, the inner end section thereof having a vertical thickness corresponding to the vertical depth of a car sill and adapted to rest upon and be secured to the outer end of the car bolster, the outer end thereof extending outwardly of the bolster end and a side-sill supporting arm extending from the outer end of the bracket body at the lower side thereof, the main body of said extension bracket having a transverse groove in its upper surface at each end adapted to receive tension truss rods.
3. The combination with a car bolster having a centrally positioned horizontal up-

per surface for the reception of central car sills and extending at each end beyond the sill seating section, extension brackets having horizontal upper surfaces and adapted to be secured upon the outer ends of said bolsters with their inner ends engaging the central car sills, and of a vertical thickness corresponding with the vertical depth of the car sills and a bunk resting upon and secured to the upper surface of the extension brackets and with said brackets and the bolster forming a truss having a recess for the reception of the central car sills.

4. The combination with a car bolster having a level top and having a side bearing surface at each end, a bracket extension adapted to be secured upon each end of the bolster having the upper surface of its main body parallel with and above the upper surface of the bolster an amount corresponding with the depth of the car sills, said bracket extensions having a side-sill supporting arm projecting from its outer end, and a bunk resting upon and secured to said extension brackets and with said brackets and the bolster forming sill-receiving recesses between them.

5. The combination with a car bolster, extension brackets secured upon the outer ends thereof and having their inner ends which overlap the bolster of a vertical depth corresponding with the depth of the central car sills, the upper surface of said extension brackets being horizontal and extending outwardly to the car side sills, said extension brackets having an integral sill supporting arm extending under the car side sill, and a metal log bunk rigidly secured to the top surfaces of the bracket extensions and extending over the car side sills.

Signed at Seattle, King County, Washington, this 30th day of June, 1922.

FREDERICK W. CHRISWELL.
